SURFACE GRINDING MACHINE

Harry L. Myers, Toledo, Ohio, assignor to The American Floor Surfacing Machine Co., Toledo, Ohio, a corporation of Ohio

Application May 9, 1932. Serial No. 610,188

10 Claims. (Cl. 51—177)

This invention relates to surface grinding machines and has more specific reference to a comparatively small light weight portable type machine particularly designed for grinding and levelling terazzo floors, monolithic slabs and the like.

By way of introduction, it is to be related that this type of floor (terazzo work) is more or less uneven as the result of rolling and trowelling and 10 any attempt to grind the surface to the requisite evenness and smoothness requires the provision of a flexible, yet rigid and sturdy machine. Generally this class of work is done by a machine of the planetary type, that is, one including a rotary 15 head or adapter plate having marginal abrasive stones or blocks.

Delving into the prior art, it would be noticed that ordinarily these blocks are rigidly secured at equi-distant circumferentially spaced points to a 20 rotary head or adapter plate. In order to cope with the uncertain surfacing conditions met in this particular line of endeavor, resiliently mounted heads are sometimes used, that is, heads which are attached by a flexible coupling to the 25 drive shaft, such as shown for example in prior Patents 1,142,570 and 1,537,279.

Despite the use of a flexibly mounted block equipped head and adapter plate and adjustable 30 mountings for the blocks, disadvantages in grinding terazzo floors are still encountered. For example, where the blocks are attached to the underside of the adapter plate in a rigid manner, the outer edge portions thereof obviously travel faster or a greater number of feet per revolution 35 than the inner edge portions of the blocks or stones. Manifestly, this differential block abrading action causes the outer edge portions of the blocks or stones to wear away far more rapidly than the inner edge portions.

40 As a matter of fact when the surfacing stones are rigidly mounted on the adapter plate practically all of the cutting is done by the inner end of the stone, causing the stone to assume a tapered or wedge-shape such as promotes inefficient 45 grinding contact with the floor. One would think that eventually the stone would wear down and get uniform contact for a short period of time on the outer end portion. This, however, is not the fact when surfacing terazzo floors because it 50 is the practice and generally necessary to spread bulk abrasive material on the floor during the grinding operation.

The abrasive is usually a fine grade of building sand and the object of distributing a fine 55 film of sand over the floor is to permit the sand

to serve as sharpening means for the abrasive stones. It has been observed that if the bulk sand or an equivalent abrasive is not used, the cutting action of the stones is materially reduced whereas when the sand is employed it repeatedly sharpens the grinding surface of the stones at 60 all times.

It is a matter of common knowledge to those skilled in this particular line of endeavor to note that the loose sand has a tendency to pile up in 65 front of the surfacing stones in the direction in which the stones are travelling. Naturally the centrifugal force tends to throw the sand to the outer end portions of the stone and after the outer end portion of the stone is gradually worn 70 away and the stone becomes tapered, the sand gradually backs up under this portion of the stone and keeps breaking away the surfacing or abrading face of the stone.

The purpose of the present invention is to 75 provide an appreciable contribution to the art and trade comprising a structure embodying the rotary adapter plate or head having the abrading stones so mounted on its marginal or peripheral portion as to compensate for wear of the stones 80 by insuring a substantially complete and constant contact of the stones themselves with the surface being ground, irrespective of the irregularities or unevenness of the floor surface.

85 Stated otherwise, I have discovered the need for abrasive stone mountings such as will function to rectify the errors of construction found in prior art devices with which I am familiar, the improved structure being designed to provide self-levelling of the abrading stones or blocks 90 while in the actual grinding work in order to provide for more exacting performance and to promote uniform reduction in the size of the stones as they are ground away.

95 A number of other features and advantages of the invention herein illustrated and described will become more clearly evident from the disclosure.

Figure 1 is a view in section and elevation 100 illustrating a small-sized terazzo grinding machine embodying the improved rocking type sub-plate or stone carrier.

Figure 2 is a top plan view of the triple arm adapter or spider plate detached from the drive 105 shaft.

Figure 3 is a fragmentary elevational view of one of the rockable block carrier units.

Figure 4 is a section on the line 4—4 of Figure 2.

Figure 5 is a view like Figure 2 showing the 110

adapter plate in plan view with the other accessories removed for clearness of illustration.

Figure 6 is a fragmentary detail section taken on the line 6—6 of Figure 5.

5 Figure 7 is a plan view of one of the block carrier or mounting devices.

Figure 8 is an end view thereof.

Referring now to the illustrative drawings and initially to Figure 1, it will be observed that the gear casing or frame is generally denoted by the numeral 9. The power driven gearing is generally designated by the numeral 10, the guard is indicated at 11, and the perpendicular rotary drive shaft is denoted by the numeral 12.

15 The improved adapter plate is recognized by the numeral 13, this being attached to the drive flange or plate 14 through the medium of a flexible coupling 15, which is an arrangement covered in previous Patents 1,142,570, and 1,537,279. Incidentally this structural ensemble serves to propel the adapter plate 13 and to render it substantially self-leveling to compensate for irregularities in the surface of the floor. No claim is made to this continuity of parts except in combination with 25 the improved features of the invention now to be described.

Referring to Figure 5, it will be noticed that the adapter plate or head 13 is of a triplex spider type. It includes a body portion 16 and a plurality 30 of circumferentially spaced equi-distant radial arms 17. Inasmuch as each arm and associated abrading stone and mounting is the same, a description of one will suffice for all. Therefore, as seen in Figure 6, the arm is formed in its underside with longitudinally spaced spring accommodation sockets 18 and formed on its top with a transverse pin or shaft bearing.

35 The abrading stone or block, which is of oblong or longitudinally elongated rectangular configuration is represented by the numeral 20 and detachably connected to the carrier or mounting unit 21. This comprises a backing plate 22 of appropriate dimensions and configuration having a sustaining flange 23 along one edge and a 45 centralized lug 24 on the opposite edge to accommodate the customary wedge (not shown) for holding the stone in place.

In its top the backing plate is provided with 50 sockets 25 registering with the superposed sockets 18. The numerals 26 designate suspension ears through which the supporting shaft or pin 27 (see Figures 3 and 4) extends. The shaft is also mounted in the aforesaid bearing 19 and held in place by a set screw 28.

55 The numerals 29 and 30 designate coiled springs located in the aforesaid complementary sockets 18 and 25, the tension of these springs being regulated through the medium of feed screws 31 threaded through appropriate openings 32 (see 60 Figure 6) in the arm 17. Incidentally, the numerals 33 designate lock nuts. In accordance with this arrangement, the block and its mounting are rockably mounted intermediate its ends and has adjustable spring means at equi-distant longitudinally spaced points on opposite sides of the pivot, permitting proper balance and regulation.

70 It is to be observed in Figure 2 that the axis of oscillation of the block mounting is not at true right angles to the radial axis of the adapter plate. This is purposely provided to permit the stones or blocks to be canted or offset with respect to the path of rotation to accomplish very important results. The object of placing the surfacing stones at this diagonal angle has two 75 effects, first it produces a shearing action on the

outer end portion of the stone; and secondly it serves to permit the stone to divert the sand and water beneath the adapter plate due to the peculiar radial scraping and sweeping action.

Otherwise the centrifugal force would have a tendency to cause the stones to throw the sand and water out instead of scooping it in and under the adapter plate.

80 At this point in the description I wish to introduce the thought that certain prior art devices with which I am familiar comprehend the broad idea of tiltable abrasive blocks and stones, using universal joints or equivalent connections. It has been observed, however, that in this type of radially tiltable stone, the stones have a tendency to wear off at both ends, leaving a convex or high portion in the center of the block when coming into contact with low spots in the floor or vice versa, the stones will hop or jump, creating a chattering condition which is sometimes so severe that it will crack the abrasive blocks. In fact, it is common experience to find large portions of the blocks chipped off with the chips becoming jammed beneath the blocks leaving irreparable grooves and scratches in the floor.

90 By way of contrast the arrangement herein illustrated and described utilizes the variable equalizing spring pressure at opposite ends of the block with the pivot point of the blocks located on a line corresponding to the path of travel, thereby 105 providing the requisite rigidity and compensating for flexibility. Moreover, the pliability of the aforesaid flexible coupling 15 for the adapter plate 13 affords a continuity of cooperation whereby the principal self-leveling condition is taken care 110 of by the adapter plate itself, and wherein the spring-pressed tiltable abrasive stones afford an added feature of accommodation and adaptation so necessary in permitting the stones to operate properly and travel in a true circular path.

115 The automatic spring resisted hinging action of the stones 20 co-operates with the heavy pressure applied on the stones by way of the machine itself, permitting the stone to maintain a substantially complete flat contact with the floor. The 120 tendency of the weight of the machine to maintain the stones in flat contact with the floor naturally compresses the inner spring 30 and relieves the outer spring 29 of excessive tension.

125 By thus compressing the inner springs 30, these springs serve to exert a downward thrust on the inner end portions of the blocks 20 and even though these inner ends travel slower than the outer ends, the pressure thus brought to bear causes said inner ends to wear away a little faster 130 than the outer ends which in turn keeps the grinding surfaces substantially flat to maintain uniform contact at all times on the surface being treated.

135 To make this feature more effective, it is permissible to tension the inner spring 30 to an even greater extent through the medium of the feed screws. Manifestly then, this differential spring pressure feature is a potent factor in conserving the stone.

140 In conclusion it is to be pointed out that where stones of this type are rigidly attached to the marginal portion of the adapter plate and no hinging action or spring balance introduced, when the outer end portions of the stones wear away, it has been the practice to reverse the stones. This practice however is detrimental in that only a portion of the stone comes into contact with the surface and frequently this portion is of such small 145 150

dimension or area as to simply groove and not grind the floor surface.

The gist of the invention, it will be understood, is in the provision of a suitable supporting frame 9 and appropriate propulsion means 10 for the perpendicular rotary shaft 12; together with the adapter plate 13 and the flexible self-leveling driving coupling 15; in conjunction with the hingedly mounted radially tiltable offset spring-pressed grinding stones and attachment means therefor assembled and operating in the manner heretofore described.

I claim:

1. In a structure of the class described, a rotary grinding head comprising an adapter plate embodying a plurality of radial arms, each arm being provided adjacent its outer end with a transverse bearing, a grinding block, attaching means for said block comprising a backing plate having quick releasable retaining means for the block, said backing plate and block being longitudinally elongated, a pair of oppositely disposed attaching ears carried by the longitudinal edge portions of said backing plate and straddling the adjacent edge portions of the arm, a shaft mounted in said bearings and ears, and coil springs interposed between the end portions of the backing plate and adjacent overlying portions of the arm.

2. In a structure of the class described, a rotary grinding head comprising an adapter plate embodying a plurality of radial arms, each arm being provided adjacent its outer end with a transverse bearing, a grinding block, attaching means for said block comprising a backing plate having quick releasable retaining means for the block, said backing plate and block being longitudinally elongated, a pair of oppositely disposed attaching ears carried by the longitudinal edge portions of said backing plate and straddling the adjacent edge portions of the arm, a shaft mounted in said bearings and ears, coil springs interposed between the end portions of the backing plate and adjacent overlying portions of the arm, and feed screws carried by said arm for regulating the relative tension of the springs.

3. In a structure of the class described, a rotary adapter plate provided in its under side adjacent the marginal portion with inner and outer sockets, a transverse bearing located between the sockets, a backing plate including means for detachably connecting a grinding block therewith, the upper side of said backing plate being formed with sockets alined with said first-named sockets, ears attached to the longitudinal edge portions of said backing plate and disposed in alinement with the end portions of the bearing, a pin mounted in the ears and bearing, and coil springs mounted in said sockets.

4. In a structure of the class described, a rotary adapter plate provided in its under side adjacent the marginal portion with inner and outer sockets, a transverse bearing located between the sockets, a backing plate including means for detachable connection of a grinding block therewith, the upper side of said backing plate being formed with sockets alined with said first-named sockets, ears attached to the longitudinal edge portions of said backing plate and disposed in alinement with the end portions of the bearing, a pin mounted in the ears and bearing, coil springs mounted in said sockets, and regulating feed screws carried by the adapter plate and co-operable with the springs for regulating the relative tension thereof.

5. In a structure of the class described, a rotary

grinding head, a grinding block, means for rockably mounting the grinding block at a point intermediate its ends on said head, and adjustable spring means associated with the head and end portions of the block to permit the inner end portion of the block to be forced yieldably and more firmly against the surface than the outer end portion thereof, whereby to insure uniform and even wearing of the block.

6. A rotary adapter plate, a grinding block, attaching means therefor comprising a backing plate having rockable hinge connection with the adapter plate at a point intermediate the ends of the backing plate, and adjustable spring means associated with the plate and located on opposite sides of the hinge connection for the purposes stated.

7. A rotary adapter plate, a grinding block, attaching means therefor comprising a backing plate having oscillatory hinge connections with the adapter plate at a point intermediate the ends of the grinding block, adjustable spring means associated with the plate and located on opposite sides of the hinge connection for the purposes stated, the axis of oscillation of said hinge connection being slightly diagonal with respect to the path of rotation of the block to permit the block to function in diverting sand and water beneath the central portion of the adapter plate under the action of centrifugal force.

8. In a structure of the class described, a rotary adapter plate including a centralized body portion and a plurality of radial arms, said arms having substantially transverse bearings intermediate their ends, said bearings being disposed at substantially diagonal angles to the circular path of rotation of the arms, a pin supported in each bearing, a grinding block, a carrier therefor having hinge means connected with the pin to permit the block to tilt radially, and variable spring means mounted on each arm and located on opposite sides of the hinge pin to permit the pressure of the inner and outer end portions of the blocks to be regulated for the purposes specified.

9. A surface grinding machine of the class described comprising a driving head, a longitudinally elongated surface grinding block, oscillatory means for rockably connecting said grinding block at a point intermediate its ends to said head, and manually regulated pressure resistant and cushioning means interposed between the end portions of the block and complementary portions of the head on opposite sides of the rockable connection to permit the inner end portion of the block to be forced yieldably and more firmly against the surface than the outer end portion thereof, whereby to insure uniform reduction of the block and positive maintenance of the complete grinding face against the surface at all times.

10. In a surface grinding machine of the class described, a rotary adapter plate, and a plurality of circumferentially spaced grinding blocks pivotally mounted on horizontal axes on the marginal portion of said plate, said blocks being radially elongated and a pivotal connection being diagonally disposed with respect to the path of movement of the blocks whereby to offset the position of said blocks in a manner to cast loose abrading material and water beneath the central portion of the adapter plate under the action of centrifugal force when the adapter plate is rotating.

HARRY L. MYERS.
